United States Patent Office.

GEORGE RICHARDS, OF RICHLAND CENTRE, WISCONSIN.

Letters Patent No. 79,005, dated June 16, 1868.

IMPROVEMENT IN WAGON-BOLSTER.

The Schedule referred to in these Letters Patent and making part of the same.

TO ALL WHOM IT MAY CONCERN:

Be it known that I, GEORGE RICHARDS, of Richland Centre, in the county of Richland, and State of Wisconsin, have invented a new and useful Improvement in Wagon or Sled-Bolsters; and I do hereby declare that the following is a full, clear, and exact description thereof, which will enable others skilled in the art to make and use the same, reference being had to the accompanying drawings, forming part of this specification, in which—

Figure 1 represents a side elevation of a bolster with my improvements attached,

Figure 2 represents a bottom view of the same, and

Figure 3 represents a view of a detached portion.

Similar letters of reference indicate corresponding parts.

This invention relates to improvements in bolsters for wagons, sleds, &c., the object of which is to provide a connection for the stakes, whereby they may be turned down out of the way, when the wagon or sled is to be loaded with any heavy article requiring to be passed over the side of the same. It consists in providing journals on the end of the bolsters, and fitting thereon metallic caps, provided with sockets, in which the stakes are to be secured, and arranging the said caps so to be held in an upright position, by a spring or other suitable means, and also so that they may be turned down out of the way when desired.

In the accompanying drawings, A represents the bolster, which is provided with a journal, whereon is fitted a metallic cap, B, which may be made of cast iron, or any other suitable metal, and provided with a socket, or other suitable means, for attaching the stake, and arranged so that it may turn on the said journal, so as to present the stake in a vertical or horizontal position.

C represents a lug, suitably secured to the under side of the bolster by screws, and having a boss or stud, a, which projects into a hole in the bolster, the more securely to hold it against lateral strain, and also provided with a recess, b, in which a spring, d, bears, which is secured to the under side of the cap B, to hold the stake in a vertical position. When it is desired to turn the stake down, the spring is pressed out of the recess by hand, which leaves the stake free to turn in either direction.

Having thus described my invention, I claim as new, and desire to secure by Letters Patent—

The combination, with the bolster A, of the cap B, spring d, and lug C, substantially as and for the purpose described.

The above specification of my invention signed by me, this 15th day of April, 1868.
